UNITED STATES PATENT OFFICE.

EDWARD A. MAYHEW, OF CHICAGO, ILLINOIS, ASSIGNOR, BY MESNE ASSIGNMENTS,
TO WALTER P. MURPHY, OF NEW YORK, N. Y.

CAR-DOOR LOCK.

Application filed February 23, 1918. Serial No. 218,688.

To all whom it may concern:

Be it known that I, EDWARD A. MAYHEW, a citizen of the United States, residing at Chicago, in the county of Cook and State of Illinois, have invented new and useful Improvements in Car-Door Locks, of which the following is a full, clear, and exact description.

My invention relates to car door fastenings and particularly to the type of fastenings in which a hasp is locked to another member by means of a lock pin or other suitable locking means and also in which a seal wire or metal ribbon is employed for indicating an unauthorized opening of the car door. In some respects the invention relates to improvements on the type of door fastener described in Letters Patent of the United States granted to R. S. Miller April 14th, 1914, No. 1,092,939.

One object of my invention is the construction of a door fastening in which the hasp or other portion of the fastening, if broken, may be replaced without necessitating the replacement of the entire fastening.

Another object is the provision of an improved hasp and locking member therefor which are not so easily broken as the existing forms of hasps and lock members by the rough usage which railway car door fastenings usually receive.

The invention consists in the novel and improved constructions, arrangements and combinations to be hereinafter described and claimed for carrying out the above stated objects and such other incidental objects as may appear from the following description of a preferred embodiment of my invention.

In the drawings:

40 Figure 1 is a front view of my improvements.

Figure 2 is a top edge view of the same showing fragments of the door-frame and the car door to which it is attached.

45 Figure 3 is a horizontal section taken on dotted line 3-3, Figure 1.

Figure 4 is a horizontal section of said improvements taken on dotted line 4-4, Figure 1.

50 Figure 5 is a vertical section taken on dotted line 5-5, Figure 1.

Figure 6 is a vertical section taken on dotted line 6-6, Figure 1.

Referring to the drawings, 1 represents the sliding car door; 2 the door post, and 3

the door-stop; 5 is a horizontal plate which is secured to the outer surface of the door with one end next the forward edge of the same, and is so constructed that its opposite end portion stands out away from the surface of the door and terminates in a loop or staple 6. The extremity 7 of this staple is provided with a cross-head or T-head 8 the lobes of which extend laterally, substantially as shown in the drawings, and this headed extremity is adapted to enter and be retained in a pocket 10 in a boss 11 in a plate 12, which latter is secured to the door in alignment with plate 5 and has a tenon 13 on the contiguous end thereof that is inserted under 70 the outstanding portion of plate 5 and enters a recess in the shoulder at the root of said outstanding part of plate 5 and prevents the lateral displacement of the one with relation to the other. The entrance to pocket 10 is 75 elongated longitudinally and corresponds in dimensions to the rectangular dimensions of head 8, and when assembling plates 5 and 12, plate 12 is first placed at right angles to plate 5 and then after the cross-head is inserted 80 through the longitudinally elongated entrance of the pocket said plates are moved into alignment and secured in this relative position to the door.

A hasp 14 is secured to staple 6 in the usual 85 manner, the eye 15 thereof being elongated longitudinally sufficiently to enable the cross-head of the staple to be passed therethrough. When the hasp is locked to the part of the door fastener that is secured to 90 the door-stop 3 the strain of the hasp will pull against the root of the staple, at which point the staple is stronger and less liable to break than the free end thereof, which, when constructed as disclosed in the afore- 95 said patent it is more liable to do.

The end of the hasp opposite the staple is provided with a head 16 that consists of an integral rectangular member which corresponds in width to the same and projects 100 at right angles to the flat sides thereof. The outer face of this head has ribs 16^a projecting outwards therefrom that strengthen it.

The locking member with which the hasp is adapted to engage to lock the door is 105 secured to the outer surface of the door stop and comprises a vertically disposed plate 17 which is secured to the outer surface of doorstop 3 by bolts or rivets 18, 18, that pass through its ends and has a thickened 110

portion or block 19 between its ends whose outer flat surface is provided at one end with a loop 20 and at the other end with a socket member 22. The socket member 5 corresponds in construction to the socket member disclosed in the said Letters Patent 1,029,939 granted to R. S. Miller, and the hasp, when the door fastener is locked, is seated between loop 20 and said socket, flat 10 against the outer surface of block 19, and so that the branch of the head thereof projecting toward the car will bear against the side of said block farthest from the car door.

Hasp 14 is held on its seat by a bolt 21 15 that corresponds in construction and operation to "bolt 10" of the aforesaid patent, and one end thereof enters and is secured in the socket 22 at one side of the hasp, and extends through loop 20 at the opposite side of said 20 hasp, and thus it is unnecessary for an elongated slot or eye to be made in the hasp for the loop to pass through as made in the hasp of the said Miller patent. The bolt of said 25 patent simply performed the function of retaining the hasp on its seat. In my invention if the portion of head 16 engaging the side of block 19 should break, the part of the head projecting outwards would engage the side of the bolt and the latter would not 30 only hold the hasp against its seat but would prevent the withdrawal of the hasp and thus keep the door locked.

What I claim as new is:

1. In a door fastener, alining horizontal 35 plates secured to a door, the one nearest the forward edge of the door having its end opposite said edge terminate in a staple the free extremity of which latter is provided with a cross-head, and the plate farthest 40 from the forward edge of the door having a pocket therein the entrance to which is the obverse of said head and elongated longitudinally, and a hasp connected to said 45 staple, in combination with a counterpart member against the outer surface of which said hasp is seated and having a socket on one side of the seat of the hasp and a loop

on the other side thereof, and a bolt for retaining the hasp on its seat whose ends enter 50 said socket and loop, said hasp having integral means which independently of said loop prevent the longitudinal withdrawal of said hasp under said bolt.

2. In a door fastener, alining horizontal plates secured to a door, the one nearest the 55 forward edge of the door having its end opposite said edge terminate in a staple the free extremity of which latter is provided with a cross-head, and the plate farthest from the forward edge of the door having a pocket therein the entrance to which is the obverse of said head and elongated longitudinally, and a hasp connected to said 60 staple, in combination with a counterpart member against the outer surface of which said hasp is seated and having a socket on one side of the seat of the hasp and a loop on the other side thereof, and a bolt for retaining the hasp on its seat whose ends enter said socket and loop, said hasp having its 65 end opposite said staple provided with a head which primarily engages the edge of its seat farthest from said door.

3. In combination with the door and door frame of a railway car, a fastening for the 70 door comprising a hasp on one of said elements and a locking member on the other having guides, a locking pin in said guides to retain the hasp, the latter formed with a transversely disposed head projecting in opposite directions from the body of the hasp, the inner portion of which head overlap and engages said locking member and the outwardly projecting portion of which stands adjacent to and in line with said pin, for the 75 purpose described.

In witness whereof I have hereunto set my hand and seal this 2nd day of February, 1918.

E. A. MAYHEW. [L.S.]
